UNITED STATES PATENT OFFICE

148,409

DESIGN FOR A BEVERAGE DISPENSER

Robert A. Doyle, Chicago, and Stephen V. Dawson, Evanston, Ill., assignors to Orange-Crush Company, Chicago, Ill., a corporation of Illinois

Application June 20, 1946, Serial No. 130,889

Term of patent 14 years

(Cl. D2—3)

To all whom it may concern:

Be it known that we, Robert A. Doyle and Stephen V. Dawson, citizens of the United States of America, residing at Chicago, in the county of Cook and State of Illinois, and Evanston, in the county of Cook and State of Illinois, respectively, have invented a new, original, and ornamental Design for a Beverage Dispenser, of which the following is a specification, reference being had to the accompanying drawing, forming part thereof.

Fig. 1 is a side elevation of a beverage dispenser showing our new design;

Fig. 2 is a rear elevation thereof;

Fig. 3 is a top plan view; and

Fig. 4 is a rear elevation.

The dominant features of the design reside in the portions shown in full lines.

We claim:

The ornamental design for a beverage dispenser, as shown and described.

ROBERT A. DOYLE.
STEPHEN V. DAWSON.
